UNITED STATES PATENT OFFICE.

ADDIE S. WHEELER, OF ZARAH, KANSAS.

DESIGN FOR A FORK.

SPECIFICATION forming part of Design No. 27,129, dated June 1, 1897.

Application filed April 6, 1897. Serial No. 631,034. Term of patent 7 years.

To all whom it may concern.

Be it known that I, ADDIE S. WHEELER, a citizen of the United States, residing at Zarah, in the county of Johnson and State of Kansas, have invented and produced a certain new and original Design for Forks; and I do declare the following to be a full, clear, and exact description of the invention, such as will enable others skilled in the art to which it app pertains to make and use the same.

My invention relates to a new and original design for a fork adapted to be used in beating butter, cream, and for many other purposes; and it consists of a fork of the shape and configuration shown in the accompanying drawings, in which—

Figure 1 is a perspective view of a fork embodying my design. Fig. 2 is a longitudinal sectional view, and Fig. 3 is a cross-sectional view.

The leading features of my design consist

in a fork composed of the handle 1, as shown, having an enlarged body portion 2, concaved longitudinally and transversely and having the square-pointed tines 3, the outer ones of which have an increased breadth and having curved outer edges and straight inner edges. A fork thus constructed will be found to be very useful for the purpose for which it is designed, and, owing to its simplicity, may be manufactured and placed upon the market to be within reach of all.

Having thus described my invention, I claim—

The design for a fork, as herein shown and described.

In testimony whereof I hereunto affix my signature in presence of two witnesses.

ADDIE S. WHEELER.
